UNITED STATES PATENT OFFICE.

WILLIAM BRONK, OF ALBANY, NEW YORK, ASSIGNOR OF ONE-HALF TO
JAMES FRANCIS BROWNE, OF SAME PLACE.

STEAM-COCK.

SPECIFICATION forming part of Letters Patent No. 239,645, dated April 5, 1881.

Application filed July 21, 1880. (No model.)

To all whom it may concern:

Be it known that I, WILLIAM BRONK, of Albany, in the county of Albany and State of New York, have invented a new and useful Improvement in Steam-Cocks, of which the following is a specification.

The object of this invention is to provide a steam-cock with a safe and self-adjustable check-valve for steam and other purposes.

10 Figure 1 is a vertical sectional elevation of the device in place on a boiler, showing the check-valve closed. Fig. 2 is a vertical elevation, partly in section, of a portion of the device, showing the check-valve opened. Fig. 15 3 is a transverse section on line *xx*, Fig. 2.

Similar letters of reference indicate corresponding parts.

In the drawings, A represents a steam-cock of ordinary construction, provided with a valve-20 stem, B, valve C, and valve-seat C'.

Projecting from the under face of the valve C is a pin, D, passing downward through the valve-seat C' and in contact with the self-adjusting valve E, which valve E projects beyond the end of the steam-cock A and has its seat in the end thereof, as shown at *a*. The stem of this valve E is slotted longitudinally, as shown at *b*, into which slot the pin or screw *c* projects through the side of the cock A, 25 whereby the said valve E is held in place with freedom to move up and down to open and to close the end of said cock A.

F represents the boiler, to which the cock A is applied, the end of the said cock projecting 30 through the shell of the boiler, as shown in Fig. 1.

When the valve C is retracted, as shown in Fig. 1, the steam in the boiler closes the valve E in its seat *a*, as shown, so that no steam can escape into or through the cock A. When 35 the valve C is but partially closed down to its seat C', the steam from the boiler will escape through the channels *f* in the sides of the valve E and out through the exit *G* of the cock A, the pin D moving the valve E from its seat *a*.

The valve C operates the same as in a valve of any ordinary steam-cock, without reference to the valve E, in shutting off or permitting 40 the escape of steam, the valve E being an

auxiliary valve of especial advantage in case of accident or when any part of the cock outside of the boiler requires repairs. Should the cock A become broken short off flush with the outer face of the boiler-sheet F, as is not unfrequently the case with steam-cocks where 55 collisions and other accidents occur on railroads, the pressure of steam within the boiler will close the valve E into its seat *a*, and thereby prevent the escape of steam to injure 60 those within the cab of the locomotive; or, should it be necessary to remove the valve or any other part of the cock A that is outside of the boiler for the purpose of repairs, the valve E will remain closed by the pressure of steam 65 within the boiler, thus obviating the usual necessity of cooling down the boiler before removing the steam-cock or its ordinary valve for the purpose of repairing it. Thus it will be seen that in case of accident to a locomotive 70 this valve E may operate as a safety-valve, and when repairs upon the cock are required it will operate to save time and the cost of cooling down the fires and refiring.

As the valve E automatically closes the 75 cock A against pressure from within a boiler or the vessel to which said cock may be applied, it is evident that said cock A may be applied to beer-barrels, gas-reservoirs, and the like with great advantage.

Having thus fully described my invention, I claim as new and desire to secure by Letters Patent—

1. The combination, with the cock A, having its rear end threaded to screw into the 85 boiler, and provided with the valve-seat *a*, of the valve E, slotted at *b*, and having a groove, *b*, working on a screw, *c*, whereby the said valve may be closed by the boiler-steam and opened by a push-pin, for the purpose specified. 90

2. The combination, with valves C E of a steam-cock, of the pin D', substantially as herein shown and described, whereby the valve E is opened as the valve C is closed, as set forth.

WILLIAM BRONK.
